UNITED STATES PATENT OFFICE.

ANDREW C. SMITH, OF LOS ANGELES, CALIFORNIA.

COMBINED SET-SQUARE AND BEVEL.

SPECIFICATION forming part of Letters Patent No. 693,075, dated February 11, 1902.

Application filed March 6, 1901. Serial No. 50,117. (No model.)

To all whom it may concern:

Be it known that I, ANDREW CLARENCE SMITH, of the city of Los Angeles, in the county of Los Angeles and State of California, have 5 invented a certain new and useful or Improved Combined Set-Square and Bevel, of which the following is a full, clear, and exact description or specification, reference being had to the annexed drawings and to the letters of reference marked thereon.

This invention, which relates to a certain new and useful improved set-square and bevel, is especially designed for use by joiners, carpenters, and other artisans occupied in the 15 construction of roofs for buildings and other branches of the art of construction or working in wood and other materials, wherein portions of timber or other material are cut to any required angle in order to be joined together in a frame or other structure.

This invention consists of a device which is an instrument wherein two blades carried in a stock are contained, which blades are movable upon separate pivots, the said blades being 25 connected movably together by a stiff link, which is so arranged that on motion being imparted to either blade movement of the other blade is also thereby produced, movement of either blade being communicated to 30 the other by means of the stiff movable connecting-link. The movements of the two blades bear a constant relationship to each other and are such that while one of the blades is limited in its range of movement to 35 about half a right angle the other blade in its movement has the range of a complete right angle, so that while one of the blades is arranged for the especial purpose of being used for marking off the angle more commonly employed than others in a vast number of instances of joints in woodwork—viz., a half right angle—yet the other blade by having its 40 range of movement more extensive is adapted for marking off a considerably larger range of angles when laid upon pieces of timber which are to be cut for joining together at any required angle. One of the blades is furthermore constructed with a circular segmental slot in it struck from the center of its 45 pivot, and the corresponding part of the other blade is in part cut away to admit of the pas-

sage of a set-bolt or clamping-screw there-through, through the stock, and also through the segmental slot of that blade which has a range of a complete right angle. The limit of 55 movement of the blades is brought about by the upper end of the segmental slot making contact with the clamping-screw, or by means of one edge of the connecting-link of the two blades coming into contact with the pivot 60 upon which the blade having the range of a complete right angle is carried, or by both of these acting together, as hereinafter described. By means of the clamping-screw the blades are fastened at any required angle 65 relatively with the straight edges of the stock, and the edges of either or both blades may be marked with or divided into scales which, being read in relation to the straight edges of the stock, at once indicate the angle at which 70 either blade is situated.

The instrument or device, as hereinbefore described, is complete in itself for nearly, if not quite, all purposes for which a set-square or bevel can be used; but when it is required 75 to use the instrument as an ordinary joiner's or carpenter's bevel then there is combined in the same instrument an ordinary bevel-blade with a slot therein, through which and through that end of the stock opposite to the 80 end wherein the blades previously referred to are carried a clamping-screw passes for clamping this bevel-blade at any required angle after the manner of an ordinary bevel.

Upon the annexed drawings, Figure 1 is a 85 front elevation of my new or improved set-square or bevel, showing the movable blades in two positions thereof. Fig. 2 is an elevation of the same, but with the upper plate of the stock removed in order to show the construction of the pivoted ends of the blades and the link by which they are connected together. Fig. 3 is an edge or side elevation corresponding to Figs. 1 and 2. Fig. 4 is an elevation of the upper end of the combined 90 set-square or bevel with the top plate of the stock removed, showing the relationship or positions of the parts when the blades are folded in parallel with the straight edges of the stock. Fig. 5 is an elevation of the inner 95 face of the upper half of the stock, showing the hollow space therein, wherein the upper 100

end of the connecting-link is capable of free movement. Fig. 6 is a front elevation of my combined set-square and bevel, showing an ordinary slotted bevel-blade carried by a 5 clamping-screw in the lower end thereof. Fig. 7 is an edge or side elevation corresponding to Fig. 6.

In Figs. 1, 2, and 3 the stock of the instrument is marked A A. In this stock A A two 10 pivots B B' are fixed, as shown at Figs. 1, 2, and 4, and upon these pivots B and B', respectively, the blades C and C' are carried, the said blades being movable angularly around these pivots. The blade C is that 15 blade whose limit or range of movement is at or about that of half a right angle, and the blade C' is that whose limit or range of movement is a complete right angle, as shown by the full range of motion of the blades C and 20 C' by the dotted lines in Fig. 1. The upper end of the blade C is cut away, as shown more particularly in Fig. 2 in the open position of the blades C and C' and at Fig. 4 in the closed position of the blades. The blade C' 25 has constructed in it the quadrantal slot D, Figs. 2 and 4, and through this slot D, through holes in each half of the stock A A, and through the open space formed in the upper part of the blade C by the portion cut away 30 therefrom the clamping-screw E passes. One end of the clamping-screw E is fixed in one half of the stock A, and the other part of the clamping-screw E, which passes through the blades and the other half of the stock A, has 35 a screw-thread cut on it, upon which a tightening nut and lever F, Figs. 1 and 3, is carried, and which nut and lever F, being turned around, upon the screw, either loosens the blades C and C' for movement or adjustment 40 in the stock A A, or clamps the blades C C' and stock A A in any required positions with each other, according as the clamping-nut and lever F is turned in a left or right hand direction.

45 The blades C and C' are connected together by a link G, Figs. 2 and 4, and by the pin connections a and b, respectively, so that when motion is imparted by hand to either of the blades C or C', by reason of their being connected movably together by the link G, motion is imparted to the other of the blades C or C'.

50 That portion of the upper blade C which is cut away is cut into such shape as to provide the projecting part to which the upper end of the link G is connected by the pin a, while the side or edge of this upper cut-away portion of the blade C which is parallel to the outer edge thereof has a recess c formed in it to enable the blade C to be moved without being interfered with by the clamping-screw E, as is clearly seen in Figs. 2 and 4.

55 The limit of range of movement of the blades is effected by the upper end of the slot 60 D making contact with the clamping-screw E or by means of one of the edges of the link

G coming in contact with the pivot B' when the blade C' is raised into the highest position or the position of a complete right angle, (shown by the dotted lines in Fig. 1,) and both 70 of these contacts may be used to operate jointly and simultaneously.

Upon the inner edge of the blade C, Figs. 1 and 2, a scale H is shown, which being read in relation to the edge I of the stock at once 75 indicates the angle at which the blade C is situated in relation to the stock. It is to be understood that the inner edge of the blade C' may also be marked with a scale which will indicate its positions in all situations of 80 the blade C' in relation to the opposite edge of the stock A A.

When the device or instrument is not in use, the blades and stock are folded together, and to facilitate opening out of the blades C 85 and C' a little hollow or recess J is formed on each side of stock A A for the purpose of allowing the user of the device or instrument to apply his thumb-nail to the point of either blade C or C', and thereby to initiate the angular movement of the blades C and C' upon 90 their pivots B and B'.

To provide room for the upper end of the link G moving freely, a curved recess K is formed in the upper end of one-half of the 95 stock A A, as shown in Fig. 4.

At Figs. 6 and 7 the blade M of an ordinary joiner's or carpenter's bevel is shown applied to the opposite end of the stock A A, wherein it is clamped in the ordinary manner by 100 means of a set-screw N and clamping-nut P, being provided with a longitudinal slot O for enabling the blade M to be moved longitudinally in relationship to the stock A A.

Having now described the nature of my 105 said invention and the best system, mode, or manner I am at present acquainted with for carrying the same into practical effect, I desire to observe in conclusion that what I consider to be novel and original, and therefore 110 claim as the invention to be secured to me by Letters Patent, is as follows:

1. The combined set-square and bevel, wherein two pivoted blades are carried in a stock having straight and parallel sides, one 115 of said blades having a circular segmental slot therein, the other of said blades having the upper part, at the side inward from its pivot removed, that is to say, recessed, and a set or clamping screw with a pinching-nut 120 passing through said stock, through said segmental slot in one of the blades and through the space or recess formed at the upper part of the other blade, the two blades being connected together at their upper ends by a link, 125 having movable connections to the upper part of each blade, said link being so shaped that when one of its edges comes into contact with the pivot-pin of that blade wherein the segmental circular slot is formed, and the 130 upper end of the circular segmental slot comes in contact with the clamping-screw, both of

said blades are prevented from being moved farther around on their pivots, or are limited in their angular movement upon said pivots, substantially as hereinbefore described.

5. 2. The combined set-square and bevel, wherein are two pivoted blades carried in a stock, having straight and parallel sides, one of said blades having a circular segmental slot, whose length is such that, when the 70
10 blade is moved to its upper limit of a right angle relatively with the stock, the upper end of said segmental slot comes in contact with the clamping-screw; the other of said blades having its upper part, at the side inward from 15 its pivot, so recessed that the clamping-screw passes through the stock of the instrument, through the recessed part of the lower blade and through the segmental slot in the other blade, the two blades being connected together 20 at their upper ends by a link having movable connections to the upper part of each blade, all operating together substantially as hereinbefore described.

3. The combined set-square and bevel, 25 wherein are two pivoted blades carried in a stock having straight and parallel sides, one of said blades having a circular segmental slot therein, the other of said blades having the upper part, at the side inward from its 30 pivot recessed, a clamping-screw with a pinching-nut, said clamping-screw passing through said stock, through the space or recess at the upper part of one blade and through the segmental slot in the upper part of the other 35 blade, the link connecting the upper parts of the blades together, said link being so shaped that when one of the blades has been raised to its limit of movement, one of the edges of said link comes in contact with one of the 40 pivots, thereby setting the limit or range of angular movement of the blades, substantially as hereinbefore described.

4. In a set-square and bevel, the combination of a straight parallel-sided stock, two 45 blades, each blade being movable upon a separate pivot, the link connecting the blades together and operating in conjunction with the pivot-pin of one of the blades and the slot whose upper end comes in contact with the 50 clamping-screw, so as to limit the range of angular movement of both of the blades, the clamping screw and nut for tightening the parts of the instrument together at any required angular position, all operating in the 55 manner and for the purposes substantially as hereinbefore described.

5. As constituting a set-square and bevel, the combination of a straight parallel-sided stock, two blades, each blade being movable 60 upon a separate pivot, the circular segmental slot in the upper end of one of the blades, the upper end of which slot comes in contact with the clamping-screw, thereby limiting the range of angular movement of both of the 65 blades, the clamping screw and nut for tight-

ening the parts of the instrument together in any required angular positions and the link connecting the upper parts of the blades together, all operating together in the manner and for the purposes substantially as hereinbefore described.

6. As constituting a set-square and bevel, the combination of a straight parallel-sided stock, two blades, each blade being movable upon a separate pivot and respectively constructed with a segmental slot in the upper part of one of the blades and a recess in the upper part of the other blade, the movable link connecting the blades together, said link being so constructed that when one of its 80 sides or edges comes into contact with one of the pivots of the instrument, the limit or range of angular movement of the blades is thereby fixed or determined, all operating together in the manner and for the purposes 85 substantially as hereinbefore described.

7. The combination of the straight, parallel-sided stock, the slotted blade at one end of said stock, the clamping screw and nut for securing said slotted blade in any required 90 angular position in said stock, the two blades at the opposite end of the stock pivoted near to the edges thereof, one of said blades being constructed with a segmental circular slot, the other of said blades being cut out or recessed at the upper end thereof to admit of the passage of the clamping-screw through the upper part of the said blades and through the said stock, the clamping screw and nut, the link connecting said blades movably, the 100 whole operating in the manner and for the purposes substantially as hereinbefore described.

8. As constituting a set-square and bevel, the combination of a straight parallel-sided 105 stock, the slotted blade at one end of said stock, the clamping screw and nut for securing said slotted blade in any required angular position in said stock, two blades pivoted at the opposite end of said stock, each blade being movable upon a separate pivot, the circular segmental slot in the upper end of one of the blades, the upper end of which slot comes in contact with the clamping-screw, thereby limiting the range of angular movement of both of the blades, the clamping 115 screw and nut for tightening the parts of the instrument together in any required angular positions and the link connecting the upper parts of the blades together, all operating together in the manner and for the purposes 120 substantially as hereinbefore described.

9. As constituting a set-square and bevel, the combination of a straight parallel-sided stock, the slotted blade at one end of said 125 stock, the clamping screw and nut for securing said slotted blade in any required angular position in said stock, two blades pivoted at the opposite end of said stock, each blade being movable upon a separate pivot and re- 130

spectively constructed with a segmental slot in the upper part of one of the blades and a recess in the upper part of the other blade, the movable link connecting the blades together, said link being so constructed that when one of its sides or edges comes in contact with one of the pivots of the instrument, the limit or range of angular movement of the blades is thereby fixed or determined, all operating together in the manner and for the

purposes substantially as hereinbefore described.

In witness whereof I, the said ANDREW CLARENCE SMITH, have hereunto set my hand, this 10th day of January, A. D. 1901, in the presence of two subscribing witnesses.

ANDREW C. SMITH.
